UNITED STATES PATENT OFFICE

2,003,526

OUTSOLE SHOE SEWING MACHINE

Fred Ashworth, Wenham, Mass., assignor to
United Shoe Machinery Corporation, Paterson,
N. J., a corporation of New Jersey

Application February 27, 1934, Serial No. 713,083

4 Claims. (Cl. 112—51)

The present invention relates to curved hook needle shoe sewing machines, and more particularly to means for adjustably positioning a gage to guide the line of the seam at a uniform distance from the edge of the work. In the illustrated embodiment, the invention is applied to a sewing machine similar to that more fully described in the patent to Ashworth No. 1,169,909, granted February 1, 1916.

10 The machine of the patent comprises a curved hook needle, a curved awl, a work support, a presser foot, and upwardly extending frame arms for supporting the needle and awl. To guide the work, an edge gage is movably arranged between the presser foot and the frame in the restricted space limited by the path of movement of the needle and awl. The edge gage is bent rearwardly to increase the space which may be occupied in properly presenting the work to the machine, 15 and is fixed to the upper end of a vertical carrier having a pivotal mounting arranged a considerable distance below the point of operation of the needle and awl to clear the arms of the frame and other parts of the machine.

20 To adjust the edge gage of the patented machine and hold it in fixed position relatively to the work support, the edge gage carrier is operated transversely of the direction of feed by mechanism acting on the carrier at the level of 25 the pivotal mounting to swing the carrier about the mounting. The vertical distance in the machine between the work support and a suitable space where a pivotal mounting for the carrier may be located without interfering with other 30 parts is such that considerable flexure of the carrier may take place, due to its necessary length. Proper rigidity of the edge gage carrier in the machine referred to is thus made difficult.

35 The object of the present invention is to simplify and improve the means for adjusting the edge gage of a sewing machine of the type referred to, so that the edge gage will be held rigidly in any desired work guiding position. A feature of the present invention contemplates the 40 provision in a sewing machine having a curved hook needle, a curved awl, upwardly and forwardly extending frame arms for supporting the needle and awl, an edge gage and an edge gage carrier pivoted on the machine below the point of 45 operation of the needle and awl, of an adjustable device engaging the upper end of the carrier to resist flexure of the carrier, and a bracket on the adjusting device having a projection engaging one of the frame arms to rigidly

brace the adjustable device against pressure of the carrier.

Other features of the invention consist in novel constructions, arrangements and combinations of parts hereinafter described and claimed.

In the drawings, Fig. 1 is a view in side elevation of a portion of the machine embodying the features of the present invention; Fig. 2 is a sectional view, taken along the line 2—2 of Fig. 1; Fig. 3 is a view in front elevation of certain parts of the machine illustrated in Fig. 1; and Fig. 4 is a detail view on an enlarged scale of the edge gage and the adjusting devices of the machine.

The machine illustrated in the drawings is substantially the same as the outsole shoe sewing machine described more fully in the patent above referred to. The machine is provided with a curved hook needle 10, a curved awl 12, a work support 14, a presser foot 16, a looper 18, an edge gage 20, and other stitch forming and work supporting devices. The needle and awl are secured to operating segments pivotally mounted on a pair of arms, one of which is illustrated at 22 extending upwardly and forwardly from the machine frame. The work is fed through the machine by the awl while in engagement with the work, the awl segment being mounted on a reciprocable stud 24 slidably mounted in the frame arms 22.

As in the machine of the Ashworth patent, the edge gage extends substantially in a horizontal direction between the work support indicated in the drawings of the present application at 14 and an arm 22, and is mounted on a vertical carrier 25 pivoted at its lower end on a stud 26 below the point of operation of the needle and awl. Adjustable mechanism is connected to the carrier close to the pivot 26, which is arranged to be actuated in changing the position of the edge gage relatively to the work support transversely of the line of work feed. Due to the length of the carrier, pressure of the work may cause the carrier to yield, thereby permitting the line of stitching to be displaced relatively to the edge of the work.

In the present form of the invention, the edge gage carrier 25 is rigidly supported near its free upper end by means of a rotatable cam 28 engaging the rearward side of a laterally extending portion of the carrier. The cam 28 is fixed to the upper end of a vertical shaft 30 rotatably mounted in a bearing bracket 31 secured at its lower end by means of screws 32 to a fixed part of the machine frame. When the shaft 30 is rotated, the cam 28 acts to move the edge gage forwardly

- or permit it to move rearwardly to the desired position.
- To strengthen the bracket 31 against thrust of the edge gage carrier, a block 34 is mounted on the bracket 31 having a bracing projection 36 extending into engagement with the front surface of the frame arm 22 at a point close to the point of engagement of the cam 28 with the carrier. The block 34 may be shifted vertically relatively to the bracket 31, so that the projection 36 will positively engage the frame arm 22. The block 34 is secured in proper adjusted position by a screw 38 passing through a slotted wing formed on the block and into a threaded opening in the bracket 31.
- To rotate the cam 28 the lower end of the shaft 30 is provided with a pinion 40 meshing with a gear segment 42 secured to the upper end of a shaft 44. The shaft 44 is rotatably mounted in a portion 46 of the machine frame, and to the lower end of the shaft is connected an arm 48 provided with set screws 50 for limiting the rotary movement of the shaft 46. The set screws 50 are positioned to engage downwardly extending lugs 52 formed on the frame portion 46. To operate the arm 48, the outer end of the arm carries a vertically arranged handle 54 located in substantially the same position as the edge gage adjusting handle of the patented machine.
- With the construction illustrated, an extremely rigid reinforcement is provided for the edge gage, the adjusting device acting within the restricted space between the edge gage and a frame arm 22 as closely as is convenient to the upper end of the edge gage carrier. Adjustment of the edge gage position is provided by simply rotating the shaft 30. The edge gage is held in firm engagement with the cam 28 by a spring 56 stretched between pins 58 on the edge gage and the bracket 31, respectively. The cam is formed with a sufficiently small diameter so as not to affect the operation of the neighboring parts, and other advantages result which will be readily understood by those skilled in the art.
- Having thus described my invention, what is claimed is:
1. An outsole shoe sewing machine having, in combination, a work support, a curved needle, a curved awl, forwardly and upwardly extending frame arms at the rear of the work support in which the needle and awl are mounted, an edge gage, a carrier therefor pivotally mounted below the work support to move transversely of the direction of feed, an adjusting device engaging the carrier adjacent its upper end arranged to resist the backward thrust of the work on the edge gage, a rotatable shaft carrying the cam, and a bracket in which the shaft is mounted, provided with a bracing projection engaging one of said frame arms.
  2. An outsole shoe sewing machine having, in combination, a work support, a curved needle, a curved awl, forwardly and upwardly extending frame arms at the rear of the work support in which the needle and awl are mounted, an edge gage, a carrier therefor pivotally mounted below the work support to move transversely of the direction of feed, an adjusting cam engaging the carrier adjacent its upper end arranged to resist the backward thrust of the work on the edge gage, a rotatable shaft carrying the cam, and a bracket in which the shaft is mounted, provided with a bracing projection engaging one of said frame arms.
  3. An outsole shoe sewing machine having, in combination, a work support, a curved needle, a curved awl, forwardly and upwardly extending frame arms at the rear of the work support in which the needle and awl are mounted, an edge gage, a carrier therefor pivotally mounted below the work support to move transversely of the direction of feed, an adjusting device engaging the carrier adjacent its upper end arranged to resist the backward thrust of the work on the edge gage, a rotatable shaft carrying the cam, and a bracket in which the shaft is mounted, provided with a bracing projection engaging one of said frame arms.
  4. An outsole shoe sewing machine having, in combination, a work support, a curved needle, a curved awl, forwardly and upwardly extending frame arms at the rear of the work support in which the needle and awl are mounted, an edge gage, a carrier therefor pivotally mounted below the work support to move transversely of the direction of feed, an adjusting cam engaging the carrier adjacent its upper end arranged to resist the backward thrust of the work on the edge gage, a vertically arranged rotatable shaft carrying the cam, a bracket in which the shaft is mounted secured at its lower end to the main frame and extending upwardly at the rear of the edge gage carrier, and a block provided with a bracing projection mounted on said bracket so as to be capable of vertical adjustment to position it in engagement with one of said frame arms.

FRED ASHWORTH.
